TIME DELAY-RELAY SWITCH

William Jones, Ely, Minn., assignor to Oliver Iron
Mining Company, a corporation of Minnesota

Application August 20, 1943, Serial No. 499,415

6 Claims. (Cl. 200—34)

This invention relates to time delay-relay switches and more particularly to such switches that are used for detonating a blasting charge. In setting off a blasting charge, while loading and preparing the blast, the wires of the detonators and the power wires leading to the blast must be individually short circuited to protect the blaster from the hazards produced by stray currents getting into the blast circuit. To do this it is imperative that the time delay-relay switch be placed comparatively close to the blasting charge.

It is an object of this invention to provide a time delay-relay switch which will keep the blast side of the circuit open from the power side and which will also operate to maintain a short circuit of both the power side and the blast side of the circuit, thus preventing a premature explosion.

A further object is to provide a means of varying the time delay interval.

Another object of the invention is to provide a time delay-relay switch of rugged construction which will protect the blaster from premature explosions due to stray currents.

These and other objects will be more apparent after referring to the following specification and attached drawings, in which:

Fig. 1 is a longitudinal section of the switch;
Fig. 2 is a cross sectional view taken on the line II—II of Fig. 1; and

Fig. 3 is a cross sectional view taken on the line III—III of Fig. 1.

Referring more particularly to the drawings the switch has a body member 2 which preferably consists of a short length of strong steel tube 4 threaded on each end for receiving pipe flanges 6 and 8. Attached to these flanges by means of bolts and nuts 10 are blind pipe flanges 12 and 14. Within the body portion of the switch intermediate the end thereof is a partition 16 secured to the body members by means of machine screws 18. The partition 16 divides the body member into two parts, a fluid cylinder 20 and a switch compartment 22.

The blind flange 12 has a hole 24 therein through which a piston rod 26 extends into the cylinder 20. A stuffing box 28 prevents loss of fluid from the cylinder 20. The piston rod has a handle 30 at its outer end and a reduced portion 32 on its inner end on which is mounted a piston 34. A leather cup type washer 36 mounted on the piston 34 prevents flow of fluid past the piston. A check valve 38 permits rapid flow of fluid from one side of the piston to the other when the piston is moving away from the parti-

tion 16 and an adjustable needle valve 40 mounted on the piston 34 permits slow flow of fluid through the piston. A spring 41 surrounds the piston rod 26 between blind flange 12 and piston 34.

A plurality of fixed electrical contacts are arranged within the switch compartment 22. Two L-shaped contacts 42 are fastened to the partition 16 by means of screws 44 and are insulated from the body 2 by means of a cylindrical insulating member 46, a disk insulator 48, insulating bushings 50 and insulating washers 52. A pair of L-shaped electrical contacts 54 are fastened to the pipe 4 by means of screws 56 which extend through the wall of pipe 4, the outer ends of the screws serving as power terminals for the power circuit. The contacts 54 and screws 56 are insulated from the body 2 by means of cylindrical insulator 46, disk insulator 48, insulating bushings 58 and insulating washers 60. Fastened to each of the L-shaped contacts 42 by means of a screw 62 is an electrical contact 64. A filler plate 66 is mounted within the pipe 4 adjacent the blind flange 14 and is held in place by means of bolts 68, one of which extends from each of the electrical contacts 64 to the outside of the body member 2 where nut 70 holds it in place. The bolt 68 and electrical contacts 64 are insulated from the body member by means of cylindrical insulator 46, disk insulator 72, insulating bushing 74 and insulating washer 76. The outer ends of bolts 68 serve as terminals in the blasting circuit. An electrical contact 78 is attached to each of the L-shaped contacts 54 by means of a screw 80, the contacts being insulated from the body member 2 by means of cylindrical insulator 46 and disk insulator 72. A switch push rod 84 extends through a hole 82 in the partition 16. Mounted on this rod within the switch compartment is a steel supporting member 86 having a pair of lugs 87 thereon which cooperate with guides 89 to prevent its turning. Mounted on the member 86 adjacent the partition 16 are a pair of flat elliptical spring brass electrical contacts 88. Another pair of flat elliptical spring brass electrical contacts 90 are mounted on the other side of member 86 at right angles to contacts 88. The contacts 88 and 90 are insulated from the member 86 by means of disk insulators 92 and insulating bushings 93. That end of the rod 84 within the switch compartment is reduced in cross section and passes through member 86. A spring 94 surrounds the reduced portion of the rod 84 and abuts against the bottom of a recess 96 in the filler member 66. A plurality of

lugs 98 are attached to the body member 2 to permit hanging of the switch on any convenient support.

The inductance of the switch is so small as to be negligible and it may be used with safety in gassy atmospheres.

The operation of the switch is as follows:

The safety switch is cocked by pulling on handle 30 until the coiled spring 41 is fully compressed. The check valve 38 releases the pressure by permitting flow of fluid through the piston 34 thus facilitating the cocking of the switch. A locking pin 100 is then inserted in a hole 102 in piston rod 26 which hole is immediately above the stuffing box 28 when the spring 41 is fully compressed. This removes the pressure from the switch push rod 84 and permits spring 94 to push the movable switch contacts 88 and 90 toward partition 16 until the contacts 88 contact fixed contacts 42 and 54. In this position one contact 88 extends between contacts 54 thus short circuiting the input terminals 56 and the other contact 88 extends between contacts 42 which are in electrical contact with fixed contacts 64 thus short circuiting the output terminals 68. After the switch is cocked and located in position by means of the pin 100 the power wires are attached to input terminals 56 and a ground wire is run from a hole 104 in one of the bolts 10 to a suitable electrical ground thus grounding the body 2. The miner then charges the blast holes and connects his detonator wires to switch terminals 68. After the blast holes are charged and all connections are made to the switch the miner pulls the pin 100 from hole 102 thus permitting spring 41 to be released. This moves the piston 34 toward the partition 16 at a speed which is governed by the setting of the needle valve 40, this determining the delay before detonation.

As the piston 34 moves toward the partition 16, the end 32 of piston rod 26 comes in contact with the end of push rod 84. The pressure of spring 41 moves the push rod 84 and compresses the spring 94. The movement of push rod 84 carries the contacts 88 out of contact with contacts 42 and 54 so that the power and blasting circuits are no longer short circuited. Continued movement of the rod 84 causes each contact 90 to contact one contact 64 and one contact 78, thus connecting the input terminals 56 to output terminals 68 to send current through the blast. The fluid in the cylinder 20 is preferably oil which will pass through the opening 82 in partition 16 into switch compartment 22. The oil in the switch compartment prevents condensation of moisture therein to remove the possibility of the moisture short circuiting the contacts and also prevents arcing within the switch.

While one embodiment of the invention has been shown and described, it will be apparent that other adaptations and modifications may be made without departing from the scope of the attached claims.

I claim:

1. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a plurality of electrical contacts mounted on said movable member, one

of said contacts normally connecting the terminals of one of said pairs of terminals, a piston rod extending through the end of said body into said cylinder, a piston connected to said piston rod, resilient means tending to force said piston toward said partition, means for permitting flow of fluid through said piston, means for holding said resilient means in compression, and means for releasing said holding means whereby the resilient means forces the piston toward said partition to move said movable member to disconnect the connected pair of terminals and to connect the input terminals to the output terminals.

15 2. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a plurality of electrical contacts mounted on said movable member, one 20 of said contacts normally connecting the terminals of one of said pairs of terminals, a piston rod extending through the end of said body into said cylinder, a piston connected to said piston rod, resilient means tending to force said piston toward said partition, means for permitting flow of fluid through said piston, means for varying the rate of flow through said piston, means for permitting flow of fluid through said piston during movement of said piston away from said partition, means for holding said resilient means in compression, and means for releasing said holding means whereby the resilient means forces the piston toward said partition to move 25 said movable member to disconnect the connected pair of terminals and to connect the input terminals to the output terminals.

3. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a supporting member attached to the other end of said movable member, a plurality of electrical contacts mounted on each side of said movable member, the electrical contacts adjacent said partition normally connecting the terminals of one of said pairs of terminals, a piston rod extending through the end of said body into said cylinder, a piston connected to said piston rod, resilient means tending to force said piston toward said partition, means for permitting flow of fluid through said piston, means for holding said resilient means in compression, means for releasing said holding means whereby the resilient means forces the piston toward said partition to move said movable member to disconnect the connected pair of terminals and to connect the input terminals to the output terminals by means of the electrical contacts remote from said partition.

4. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a plurality of electrical contacts mounted on said movable member, one

tudinally movable member mounted in said compartment having one end thereof extending through said partition, a supporting member attached to the other end of said movable member, a plurality of electrical contacts mounted on each side of said movable member, the electrical contacts adjacent said partition normally connecting the terminals of one of said pairs of terminals, a piston rod extending through the end of said body into said cylinder, a piston connected to said piston rod, resilient means tending to force said piston toward said partition, a needle valve on said piston permitting flow of fluid therethrough, means for varying the rate of flow through said piston, means for permitting flow of fluid through said piston during movement of said piston away from said partition, means for holding said resilient means in compression, means for releasing said holding means whereby the resilient means forces the piston toward said partition to move said movable member to disconnect the connected pair of terminals and to connect the input terminals to the output terminals by means of the electrical contacts remote from said partition.

5. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a supporting member attached to the other end of said movable member, a plurality of electrical contacts mounted on each side of said movable member, the electrical contacts adjacent said partition normally connecting the terminals of one of said pairs of terminals, a piston rod extending through the end of said body into said cylinder, a piston connected to said piston rod, a spring surrounding said piston rod tending to force said piston toward said partition, a needle valve on said piston permitting flow of fluid through said piston, said piston rod extend-

ing through said piston, means on said piston rod for holding said spring in compression, said spring upon release of said holding means forcing the piston toward the partition so that after an interval of time the extension of said piston rod will contact the end of said movable member and move it to disconnect the connected pair of terminals and to connect the input terminals to the output terminals by means of the electrical contacts remote from said partition.

10 6. A time delay switch comprising a body, a partition in said body dividing it into a fluid cylinder and a switch compartment, a pair of input terminals connected to said body within said compartment, a pair of output terminals connected to said body within said compartment, a longitudinally movable member mounted in said compartment having one end thereof extending through said partition, a supporting member attached to the other end of said movable member, a plurality of electrical contacts mounted on each side of said movable member, the electrical contacts adjacent said partition normally connecting the terminals of one of said pairs of terminals, a piston rod extending through the end of said body into said cylinder, a piston connected to said piston rod, a spring surrounding said piston rod tending to force said piston toward said partition, a needle valve on said piston permitting flow of fluid through said piston, a check valve on said piston permitting flow of fluid through said piston during movement of said piston away from said partition, said piston rod extending through said piston, means on said piston rod for holding said spring in compression, said spring upon release of said holding means forcing the piston toward the partition so that after an interval of time the extension of said piston rod will contact the end of said movable member and move it to disconnect the connected pair of terminals and to connect the input terminals to the output terminals by means of the electrical contacts remote from said partition.
